T. E. STARR

RHEOSTAT ACCESSORY

Filed April 3, 1925

Inventor

Thomas Elmer Starr,

By

Plamme & Dina

Attorney

UNITED STATES PATENT OFFICE.

THOMAS ELMER STARR, OF STEPHENVILLE, TEXAS, ASSIGNOR OF ONE-HALF TO
W. S. RAMSAY, OF STEPHENVILLE, TEXAS.

RHEOSTAT ACCESSORY.

Application filed April 3, 1925. Serial No. 20,462.

This invention relates to a rheostat for controlling the charge rate of a generator and is particularly adapted for use on Ford automobiles. This rheostat control gives 5 the operator the advantage of changing the output of the generator from city driving to country driving, without the necessity of leaving his seat or stopping the automobile. It is well known that a much heavier 10 charge rate is required in city driving, to keep the battery properly charged, especially where the starter and lights are frequently used. With the battery charging at this rate, it would be very injurious to the 15 battery and generator to drive the car at a high rate of speed for several hours, but with this device, the driver will have perfect control of the output of the generator.

Another important object of the invention 20 is the insertion of fuses in the field circuit of the generator, whereby it is impossible to burn out the armature, field coil, or lights.

With the above and numerous other objects in view, as will appear as the description 25 proceeds, the invention consists in a certain novel arrangement as will be herein-after more fully described and claimed.

In the drawing:

The figure is an elevation, partly in section, of the improved rheostat with the circuits associated therewith, shown diagrammatically.

Referring to the drawing in detail, it will be seen that 1 designates the circular casing, which is provided with an annular flange 2, in order that it may be mounted on the dash board of an automobile, within easy reach of the operator. An arcuate member 3 is mounted in the casing, in any 35 suitable manner, such as by means of screws 4, and has a resistance coil 5 wound thereabout. An arm 6 is swingable by a shaft 7 and the end thereof moves over the convolutions of the resistance coil 5. The wires 40 8 and 9 form a part of the field coils of a generator. The wire 8 is attached to a screw 10, from which extends a wire 11, connected to the arm 6. The wire 9 is con-

nected to a fuse 12, from which extends the wire 13, connected to one end convolution 50 of the resistance coil 5. The wire 14 leads to the ammeter from a fuse 15, mounted in the casing, and the wire 16 leads from this fuse to the ignition and lighting switch. The two fuses are thus conveniently located and can be repaired very quickly and easily, when necessary.

It will be evident that the charging rate of the generator may be controlled by moving the arm 6 over the convolutions of the 60 resistance coil, thus increasing or decreasing the field of the generator, and thus the battery may be charged at whatever desired rate may be found necessary from experience. The fuse 12 will protect all parts 65 of the generator from becoming burnt up, and will also protect the battery from becoming overcharged, or charged too fast. It is thought that the construction, operation and advantages of the invention will now 70 be clearly understood by those skilled in the art, without a more detailed explanation.

It is desired, however, to point out that numerous changes in the details of construction, in the combination and arrangement 75 of parts may be resorted to, without departing from the spirit or scope of the invention, as hereinafter claimed, or sacrificing any of its advantages.

Having thus described my invention, what I claim as new is:

An accessory of the class described including a cylindrical casing, an arcuate member in one-half of the casing disposed 85 concentrically therewith, a resistance coil disposed about the arcuate member, an arm swingably mounted in the casing and having its end movable over the convolutions of the resistance coil, and a pair of fuses 90 in the other half of the casing disposed in parallel spaced relation with each other.

In testimony whereof I affix my signature.

THOMAS ELMER STARR.
